UNITED STATES PATENT OFFICE.

CARL E. STRUNCK, OF HENDERSONVILLE, NORTH CAROLINA.

DISPLAY STAND.

Application filed April 27, 1926. Serial No. 104,966.

The invention relates to display stands by means of which merchandise of various kinds may be exhibited in a convenient and attractive manner.

5 The principal object of the invention, generally stated, is to provide a display stand which is adjustable as to height so that goods of any desired kind may be disposed at a preferred elevation, depending upon their nature, lighting effects and other circumstances which may enter into the matter.

An important object of the invention is to provide a display stand having very simply constructed means for holding the parts at 15 a desired adjustment.

A further object of the invention is the provision of a display stand or the like in which the relatively movable elements will be normally locked against movement, a 20 positive action being required on the part of the operator to effect release of the holding means so that the adjustment may be varied to meet conditions.

Still another object is to provide a device 25 of this character in which the locking or holding means is of such formation that any wear on the relatively movable parts will be automatically taken up and any looseness consequently prevented, the length of life 30 being therefore materially increased.

An additional object of the invention is to provide a device or structure of this character or of a similar nature which will be simple and inexpensive to manufacture, easy 35 to set up and use, convenient in action, efficient and durable in service, and a general improvement in the art.

To the attainment of the foregoing and other objects and advantages such as will 40 hereinafter appear, the invention preferably consists in the details of construction and the arrangement and combination of parts to be more fully described and claimed, and illustrated in the accompanying drawing in 45 which:

Figure 1 is a side elevation of the complete device,

Figure 2 is a fragmentary elevation taken at right angles to Figure 1 and looking at 50 the releasing lever, and

Figure 3 is a detail longitudinal section on a slightly larger scale.

Referring to the drawings in detail, the device is represented as including a preferably weighted base 1 of any desired size, shape and material, and from which rises a

tubular standard 2 on which is mounted, as for instance by threading, a housing or casting element 3 which may conveniently be formed as a casting, stamping or pressing 60 and which may have any requisite dimensions. This member 3 is shown as socketed at its lower end, at 4, and provided with an inwardly extending flange 5 for a purpose to be described.

65 The stand further includes a rod-like member 6 telescopically engaged within the standard 2 and slideable through an opening 7 at the top of the member 3. A collar or enlargement 8 may be provided on the lower 70 end of the rod member 2, which collar is adapted to engage against the shoulder 5 for the purpose of preventing withdrawal of the member 2 from the relatively stationary portion of the stand. Clearly, the rod member 75 may have any preferred upper end construction indicated at 9, depending upon the nature of the goods or articles to be displayed.

An important feature of the invention is the provision of peculiar and novel means 80 for holding the rod 6, and goods carried thereby, at any desired height. The mechanism for this purpose is here disclosed as including or comprising a vertically slideable wedge 10 provided at one side with a leather 85 or other similar friction shoe 11 adapted to bear against the rod 6. The member 3 is provided at its inner surface with an inclined wall portion 12 against which the wedge is slidably engaged. A coil spring 13 90 urges the wedge downwardly into active position, this spring abutting against the top of the wedge and against the underside of an ear 14 at the edge of an opening 15 in the side of the member 3.

95 For effecting release of the locking wedge so that the rod 6 may be moved with respect to the standard 2, I have shown a thumb lever 16 pivoted at 17 within the opening 15, the thumb lever being of angular shape and having a rod 18 or the like pivoted upon its inner end and connected with the wedge.

100 In the use of the device it will of course be seen that under normal circumstances the pressure of the spring against the wedge will force the latter against the inclined wall or surface 12, the result being that the shoe 11 will be crowded against the rod 6 and will engage it frictionally with sufficient pressure 110 to maintain the rod 6, and any goods or articles supported thereby, in the desired ad-

justed position and against any possible accidental movement.

In case a change in the position of the rod 6 is needed, it is merely necessary to 5 press upon the thumb lever 16 and, by means of the rod or connection 18, move the wedge 10 upwardly. As the wedge rides along the inclined surface 12 its crowding action 10 against the rod 6 will be relieved and the rod may then be moved freely with respect 15 to the remainder of the device. When the parts are then in the proper position, release of the pressure upon the thumb lever will permit the spring 13 to return the wedge 15 to its locking position.

From the foregoing description and a study of the drawing it will be apparent that I have thus provided a simply constructed and very easily adjusted display 20 stand capable of use for a wide variety of purposes and one which possesses the great advantage of eliminating the use of set screws such as are commonly provided, it being well known that when such set screws 25 are lost a stand is at least temporarily useless.

While I have shown and described the device as a display stand, it should be understood that the same locking means may be 30 used in connection with any type of apparatus in which it is desirable to hold one telescopic member against movement with respect to another with which it cooperates. It should also be understood that I reserve 35 the right to make such changes in the details and the arrangement as will widen the field of utility and increase the adaptability of the device, provided such changes, modifications or variations constitute no departure from the spirit of the invention or the 40 scope of the claims hereunto appended.

Having thus described the invention, I claim:

1. In a structure including a base, a tubular standard rising therefrom, and a casing member carried by the standard, a rod slidably mounted within the standard and extending through the casing member, said 45 casing member having an inclined inner

surface, a wedge slidably mounted within 50 the casing member and having an inclined side coacting with said inclined surface whereby to be crowded against the rod, an abutment element in the casing member, a spring engaging the abutment element and 55 the wedge, and lever operated means slideable through the abutment member and connected with the wedge for moving the same out of engagement with the rod to permit movement of the latter. 60

2. In a structure including a base, a tubular standard rising therefrom, and a casing member carried by the standard, a rod slidably mounted within the standard and extending through the casing member, said 65 casing member having an inclined inner wall, a wedge slidably mounted within the casing member and having an inclined side coacting with said inclined surface whereby to be crowded against the rod, an abutment 70 element in the casing member, a spring engaging the abutment element and the wedge, means for releasing the spring tension, comprising a pivoted angle lever mounted on the casing member, the casing member having an opening accommodating and permitting movement of the lever, and an element 75 pivotally connected with the inner end of the lever, slideable through the abutment element and connected with the wedge. 80

3. In a display stand, a base, a tubular guide rising therefrom, a casing at the upper end of the guide, a rod slideable through the casing and telescopically engaged with in the tubular guide, a stop shoulder at the juncture of the casing member with the guide, a collar on the rod cooperating with said shoulder for preventing withdrawal of the rod from the guide, the casing member having an inclined inner surface, a spring 85 pressed locking wedge cooperating with said inclined surface and frictionally engageable with the rod for holding the latter stationary, and lever means extending laterally from the casing and connected with the wedge for moving it to released position. 90

In testimony whereof I affix my signature.

CARL F. STRUNCK.
